POWDER DISTRIBUTORS

Chester W. Robinette, St. Louis County, Mo., assignor to
Getz Exterminators, Inc., St. Louis, Mo., a corporation
of Missouri

Filed July 7, 1961, Ser. No. 122,530
3 Claims. (Cl. 43—146)

This invention relates to improvements in powder distributors adapted for use particularly with insecticides, fungicides, rodenticides, and other materials capable of being handled and distributed in such manner.

Distributors have been provided heretofore for this purpose, but due to the construction thereof, these have not had all of the advantages of which such devices are capable, and it has been desirable to make improvements therein.

One object of this invention is to improve the construction and handling of such distributors for various powdered materials.

Another object of the invention is to provide for a stopper closure in the distributor, with provisions for effective sealing of the stopper when inserted therein, with a tight joint therebetween.

Still another object of the invention is to provide a hook or handle on the distributor to facilitate carrying and handling thereof without adding appreciably to the complexity or cost of the structure.

These objects may be accomplished, according to one embodiment of the invention, which is illustrated in the accompanying drawings, in which:

FIG. 1 is a vertical sectional view through the distributor on the line 1—1 in FIGURE 2;

FIG. 2 is a horizontal section therethrough, on the line 2—2 in FIG. 1; and

FIG. 3 is a side elevation of the distributor on a smaller scale.

The distributor illustrated as an embodiment of this invention comprises top and bottom members 1 and 2, connected together by a collapsible side wall section 3. These parts cooperate to form a container for the material to be distributed and discharged therefrom.

The top element 1 is formed with an end wall section 4, having a surrounding inturned sleeve 5 spun or otherwise formed on the end wall 4 and extending downwardly therefrom. The end wall 4 is provided with a filling opening 6 therein, having a downturned flange 7 around the filling opening to provide a smooth edge thereon. The stopper 8 is adapted to be inserted in the filling opening 6. The inturned flange 7, formed around the filling opening 6, provides a tight joint between the stopper 8 and the top element 1. The stopper 8 may be formed of any suitable material and preferably is of cork, rubber or other cushion material suitable for the purpose.

The bottom member 2 is provided with a bottom closure wall 9 having an upturned sleeve section 10 formed thereon, as by spinning or otherwise, so as to provide a bottom closure and cup-like portion for the dispenser.

The side wall section 3 preferably is collapsible, to effect a bellows action for the dispenser. In this embodiment, the section 3 is formed as a rubber or elastic sleeve telescoped at its opposite ends over the sleeve sections 5 and 10 formed on the top and bottom members 1 and 2. The overlapped edges of these parts are preferably secured tightly together as by wire or other form of clamps, indicated generally at 11. Each of the sleeve sections 5 and 10 is formed preferably with an annular circumferential indentation 12 therein, so as to permit the clamps 11 to force portions of the elastic sleeve 3 into the circumferential indentations and thereby effect a tight connection between the surrounding sleeve 3 and the end members 1 and 2.

2

A coiled spring 13 extends axially between the end walls 4 and 9 to assist the elastic sleeve 3 to return these parts to expanded position when collapsed.

The bottom member 2 is provided with an opening 14 in the sleeve section 10 thereof through which a tubular discharge spout 15 extends from a point diametrically across the bottom member 2, as will be apparent from FIGS. 1 and 2. The discharge spout is formed somewhat conical, to facilitate the discharge of the material. The opposite sides of the spout 15 are provided with openings 16 in the section thereof within the dispenser forming inlets for the powdered material. The end of the tubular spout within the dispenser is closed by being pinched together, as indicated at 17, and preferably abuts directly against the adjacent sleeve section 10 on the bottom member 2. This spout may be attached to the bottom member at this point by being secured in any suitable manner, as, for example, by soldering, welding, or the like.

A hook or handle 18 is provided on a side of the distributor adjacent the bottom thereof. This hook or handle is made of wire which protrudes through the sleeve section 10 on the bottom member 2, with its inner end being curved around the inside surface of the sleeve section 10 through more than 180°, as indicated at 19. The inner end section 19 should be secured effectively to the bottom member 2 as by soldering, welding, or the like, and it may overlap the pinched end 17 so as to utilize one point of fastening for both elements, as well as aid in retaining the spout in place.

The outer end of the wire handle 18 extends radially outward from the sleeve section 10 on the bottom member 2 to a desired extent, as for example, $\frac{1}{2}$ inch, and then is turned upward, as indicated at 20, with the extreme end thereof bent back upon itself at 21. This leaves an opening between the container wall 3 and the hook portion 20 of about $\frac{1}{2}$ inch, to facilitate handling and carrying of the distributor, and it also permits the distributor to be turned upside down and to be hooked over a suitable support in such inverted position when stored or when not in use.

In using the distributor, the powdered material is introduced into the container through the inlet opening 6, after which the stopper 8 is applied thereto and closes effectively the inlet opening. This powder is discharged from the distributor by an endwise collapsing of the sections 1 and 2 through an axial compression applied thereto. Such movement causes the elastic wall 3 to collapse in a somewhat bellows action and, due to the elasticity thereof as well as the action of the coil spring 13, the end members 1 and 2 are restored to their extended relation. The powder is discharged through the openings 16 from the interior of the container and through the spout 15 upon such collapsing movements.

The distributor is capable of use with any suitable material which is to be dispensed in powder form, such, for example, as insecticides, fungicides, rodenticides, etc.

The distributor may be handled by the hook or handle 18, and when not in use, may be inverted and hooked over a suitable support, such as a nail, bar, etc.

While the invention has been illustrated and described in one embodiment, it is recognized that variations and changes may be made therein, without departing from the invention as set forth in the claims.

I claim:

1. A distributor of the character described comprising top and bottom members each having an inturned sleeve section thereon, a collapsible wall member telescoped with the sleeve sections and connected thereto, a discharge spout extending radially outward from the bottom member with its inner end projecting substantially diametrically across the latter and having a discharge opening therein, a hook-shaped handle connected with the bottom

member and extending laterally therefrom, said handle including an inner portion overlapping the inner end of the discharge spout and secured to the bottom member, and an outer portion turned upward along the outer surface of the distributor and outwardly spaced therefrom and forming an outwardly projecting hook for suspending the distributor.

2. A distributor comprising a container including top and bottom members each having inturned sleeve sections thereon, the top member including a filling opening with a surrounding flange and a closure inserted into the opening, a wall member of collapsible material telescoped over the sleeve sections of the top and bottom members and secured thereto, a coil spring interposed between the top and bottom members tending to restore the latter upon collapsing, a discharge spout extending diametrically across the bottom member and outwardly through the sleeve section thereon for discharging material from within the container, said spout having one or more openings in the inner end thereof within the container, and a hook member formed of wire with an inner end section extending around the inside of the sleeve section on the bottom member overlapping and being secured to the inner end of the spout as well as being secured to the bottom

member by a unitary securing means, said wire extending radially outward through the sleeve section on the bottom member and upwardly substantially parallel with the wall member in outward spaced relation from the latter forming a hook thereon.

3. A distributor of the character described comprising top and bottom members, a collapsible wall connecting said top and bottom members, a unitary discharge spout extending through a hole in the bottom member and extending diametrically across said bottom member above the bottom thereof and detached from the bottom, a handle having an outer portion extending externally of said collapsible wall member and an inner portion overlying the inner end of said discharge spout, said inner portion of said handle being connected to said bottom member whereby the positioning of said inner portion of said handle holds said discharge spout in place.
